(57) **CLAIM**

I claim the ornamental design for a tire, as shown and
described.

DESCRIPTION

FIG. 1 is a perspective view of a tire showing our new design,
it being understood that the pattern repeats uniformly
throughout the circumference of the tread;

FIG. 2 is a front elevational view thereof;

FIG. 3 is a right side elevational view thereof;

FIG. 4 is a left side elevational view thereof; and,

FIG. 5 is an enlarged fragmentary front elevational view
thereof.

In the drawings, the broken lines defining the sidewall, inner
bead and the peripheral boundary between the tire tread and
the sidewall are for illustrative purposes only and form no part
of the claim design.
